UNITED STATES PATENT OFFICE.

HARTLEY B. PRATT, OF BARROW-IN-FURNESS, ENGLAND, ASSIGNOR TO VICKERS LIMITED, OF WESTMINSTER, LONDON, ENGLAND.

SUBMARINE MINE.

Application filed September 10, 1923. Serial No. 661,754.

To all whom it may concern:

Be it known that I, HARTLEY BLYTH PRATT, a subject of the King of Great Britain, residing at Naval Construction Works, Barrow-in-Furness, in the county of Lancaster, England, have invented certain new and useful Improvements in or Relating to Submarine Mines, of which the following is a specification.

10 This invention relates to submarine mines of the kind that are fired by means of an electric current which is usually generated by the formation of a battery on one of the horns of the mine being struck by a passing vessel or otherwise and in which safety devices are provided controlled by the tension of the mooring rope for completing automatically the electric circuit on the mine being anchored or breaking the same on the

15 mine being parted from its moorings.

In mines of this type a shaft or equivalent member is usually provided which is adapted to slide inwards or outwards of the mine casing and which has its lower end connected to the mooring cable, the variation in the tension of the latter acting against the resistance of a spring and determining the position of the electric switch elements. In order to maintain the parts watertight a 20 flexible diaphragm, usually composed of rubber, has been located around the aforesaid shaft or equivalent sliding member. In practice, this arrangement has been found to be objectionable on account of the fact that the hydrostatic pressure acting on the 25 flexible diaphragm is opposed to the buoyancy pull on the movable shaft, and at considerable depths, say 175 feet, the resultant effort is insufficient to ensure that the safety 30 switch will remain closed when the mine is struck by a passing vessel. At greater depths the hydrostatic pressure acting on the diaphragm itself may even be greater than the buoyancy pull, in which case the safety 35 switch will be maintained permanently open and the mine rendered inoperative.

According to the present invention the buoyancy pull upon the aforesaid sliding shaft or equivalent member is adapted to 40 push the sliding shaft inwards instead of pulling it outwards while the flexible diaphragm which maintains the parts watertight is adapted to be pushed inwards instead of being pulled outwards. The con-

tacts forming part of the electric circuit of the mine are also adapted to be completed by the upward movement of the sliding shaft instead of the downward movement of the said shaft.

Owing to this arrangement the hydrostatic pressure, when the mine is anchored in deep water, tends to push the sliding member inwards and thus to keep the switch closed. Consequently, the improved mine will be operative at any depth at which it may be anchored. The power of the spring which controls the movement of the sliding shaft is only limited by that which will permit the buoyancy pull (unassisted by hydrostatic pressure) to keep the switch closed when the mine is laid near the surface. Consequently, and with a mine buoyancy of 400 lbs or more a spring can be fitted to exert a thrust of 300 lbs which is sufficient to support the weight of mooring rope and ensure that the switch will be opened and the mine kept safe if it should come adrift with 1,500 feet of .94 circumference wire rope hanging free. In the older construction of submarine mine the strength of the controlling spring could not be increased without reducing the working depth and with the spring which has heretofore been used in practice the switch could only be maintained open when the mine was adrift with less than 400 ft of .94 mooring rope hanging free as with any greater length of mooring rope the mine still remained active when adrift. Furthermore and with the improved construction above referred to the flexible diaphragm is pushed into operative position and rests on a dished metal plate. Thus the rubber is relieved from tensile stress and will last longer than diaphragms which, as in the existing standard type of mine, are unsupported against hydrostatic pressure when in the operative position.

According to a further feature of the present invention the detonator and primer are maintained out of the relative firing position until the mine has been launched and anchored to the sea bed by a catch which is removed to allow the primer and detonator to take up the firing position by the upward movement of the shaft or equivalent member which serves to bring about the completion of the electric circuit.

According to another feature of the pres-

ent invention a delay action device may also be provided which prevents the tension in the mooring cable from providing the necessary movement either to complete the electric circuit and to allow the primer and detonator to take up the relative firing position until after a predetermined interval of time, the said device comprising a soluble plug located within a chamber provided at the lower part of the mine, the chamber having openings through which water is allowed to enter and act on the soluble plug, the said latter being brought opposite the said openings to allow ingress of sea water to the plug by the upward movement of the sliding member which controls the electric circuit.

In order that the said invention may be clearly understood and readily carried into effect the same will now be described more fully with reference to the accompanying drawings which show by way of example a submarine mine constructed according to the present invention and in which:—

Figure 1 is a part sectional elevation of the flotation chamber of a submarine mine.

Figure 2 is a detached elevation on a large scale of the tension controlled mechanism for making the electric circuit and at the same time allowing the primer to be brought into firing position relatively to the detonator.

Figure 3 is a sectional elevation corresponding to Figure 2, showing the parts reversed.

Figure 4 is a view at right angles to Figure 3, showing the casing for the primer and the electric detonator.

Figure 5 is a top plan view on a larger scale of the mechanism shown at Figure 2 and

Figure 6 is a plan of the bottom of the flotation chamber showing a releasing device which is manually operated to release the parts of the firing mechanism prior to the mine being launched.

1 is the flotation chamber or mine proper. 2, 2 are the horn batteries. 3 is the chamber containing the main bursting charge. 4 is the slidably mounted primer and 5 is the electric detonator. The internal construction of the detonator has not been shown as it forms no part of the present invention. 6 is a push rod forming part of the aforesaid sliding member. 7 is a lever pivotally attached to a bracket 7^a on the lower part of a hollow box-like casting 14, one end of the said lever being connected to the mooring cable 8 and the other end 9 bearing against a nut 10 mounted upon a screw thread on the lower extremity of the push rod 6. 11 is a split pin which extends through the lower part of the hollow casting 14 and is normally positioned in a recess above the nut 10 so as to restrain its movement, the

said pin 11 forming part of a safety device and being provided with a hand grip 12 by means of which the pin 11 can be withdrawn prior to launching of the mine so as to release the tension controlled parts of the mine.

13 is the diaphragm which serves to maintain the parts watertight, the said diaphragm being located between the casting 14 and the mechanism plate or support 21. Sea water is allowed free access to the chamber 14^a beneath the diaphragm through openings 15. Owing to this arrangement the diaphragm 13 when the mine is launched is subjected to the hydrostatic pressure of the water which presses it inwards against a conical seating 13^a. The rubber will thus be relieved from tensile stress and will last longer than diaphragms unsupported against hydrostatic pressure when in operative position.

The upper part of the push rod 6, in the example shown, is attached to a hollow plunger 16 slidably mounted within an extension 21^a of the mechanism plate 21 and within the said plunger a helical spring 17 is located. The lower extremity of the plunger 16 has a screw threaded part 16^a and is clamped to the flexible diaphragm 13 by a nut 16^b and a washer 16^c. The plunger 16 is attached to the upper end of the push rod 6, the rod 6 to this end being formed with a projection 6^a which engages within a notch in the lower end of the plunger 16. The upper part of the spring 17 is located within a cap 18, which is attached by sleeve nuts 19, 19 and bolts 20, 20 to the extension 21^a of the mechanism plate 21. It will be observed that one of the bolts 19 extends through an opening 22 in the plunger 16 and thus acts as a guide therefor.

The plunger 16 is provided with a pair of lateral extensions 16^a, 16^a having insulated bushes 16^e, 16^e within which are located recessed electric contact pieces 16^b, 16^b (see Figures 3 and 5). 23, 23 are spring controlled plungers which are mounted within casings or cylinders 23^a bolted to the mechanism plate 21 and located contiguous to the recessed contact pieces 16^b, 16^b.

24, 24 are electric leads in circuit with the horn batteries and with the electric detonator and which are attached to the outer extremities of the plungers 23, 23. It will be clear that on account of this arrangement and when the contact pieces 16^b, 16^b are positioned between the spring pressed plungers 23, 23 the electric circuit from the horn batteries through the detonator will be completed. Normally, however, the contact pieces 16^b, 16^b are held out of engagement with the spring pressed plungers 23, 23 until the tension on the mooring cable acting, through the pivoted lever 7, raises the push rod 6 and moves the plunger 16 in an upward direction.

25 is the primer casing which is cast integral with the plate 21. In Figures 2,

3, 4 and 5 the primer has been removed for the sake of clearness but as will be clear from Figure 1 the primer is normally held out of contact with the electric detonator 5 by means of a trip lever 26 positioned between bosses 26^a on the primer casing 25 and connected thereto by means of a pivot pin 26^b. The trip lever 26 is normally held in the position shown in the drawings by 10 means of tension springs 27, 27 disposed on opposite sides of the primer casing 25 one end of each of the said springs 27 being connected to the casing at 27^a and the other end being attached to the top of the trip lever 15 at 27^b (Figure 2). When in this position the end of the trip lever projects in the path of movement of the sliding primer 4 and normally retains the same in the raised position shown at Figure 1. When, however, the push rod 7 and consequently the 20 plunger 16 is raised and the spring 17 compressed owing to the tension exerted on the lever 7 by the mooring cable 8, the boss 22^a on the plunger 16 presses the trip lever 26 25 inwards against the influence of the springs 27 and moves the same out of the path of movement of the primer 4 so that the latter falls into contact with the electric detonator 5. Should the mine break from its moorings the spring 17 will return the plunger 16 30 to its original position and thereby remove the contact pieces 16^a, 16^b out of contact with the spring pressed plunger 23, 23. The electric detonator is placed in circuit with 35 the electric horns by means of spring pressed plungers 28, 28 bolted to the primer casing by insulated supports 28^a the inner ends of the said plungers 28, 28 pressing against copper contact pieces surrounding the electric 40 detonator.

The auxiliary safety device for maintaining the parts out of action until the mine has been launched for a predetermined interval of time, is constituted by a soluble plug 31 positioned around the lever 6 and acted upon by a spring pressed plunger 32 which normally maintains the soluble plug in the position shown at Figure 3. On either side of the soluble plug 31 are rubber rings 33, 33. On the mine being launched and being anchored to the sea bed the tension on the mooring cable causes the end of the lever 7 to raise the push lever 6. The plunger 32 is also raised slightly against the resistance of its spring thereby bringing the soluble plug 31 opposite openings 35, 35 in the casting 14. The sea water thereupon acts on the soluble plug 31, and dissolves the same and thereafter the lever 6 is permitted to be raised (assisted if desired and as shown by the hydrostatic pressure acting on the diaphragm 13) to the extent which is necessary to bring the contact pieces 16^a, 16^b opposite the spring pressed plunger 23, 23 thus completing the electric circuit

through the detonator and simultaneously allowing the primer and detonator to move into the relative firing position.

What I claim and desire to secure by Letters Patent of the United States is:—

1. A submarine mine comprising an electric circuit, contact devices which explode the mine automatically when struck by a moving body, and a safety device, controlled by the tension of the mooring cable which automatically makes or breaks the electric firing circuit, said safety device comprising a switch element located within the mine casing, a movable switch element also located within the mine casing, means which maintain said movable switch element out of contact with the other switch element when the mine is not anchored, a member which on the mine being anchored moves automatically upwards relatively to the mine casing and closes the firing circuit of the mine, a pivoted lever one end of which acts upon said member, and a connection from the other end of said pivoted lever to said mooring cable for controlling the automatic movement of said member.

2. A submarine mine comprising a flotation chamber containing an electric firing circuit, contact devices which explode the mine automatically when struck by a moving body, an anchor adapted to separate from said flotation chamber and to descend to the sea bed, a mooring rope and a safety device connected to and controlled by the tension of the mooring cable and comprising fixed switching means located within the mine casing, movable switching means also located within the mine casing, spring means tending to maintain said movable switching means out of contact with said fixed switching means, and a pivoted lever one end of which is connected to the mooring cable and the other end of which bears upon said movable switching means, said lever immediately the mine is anchored serving to automatically lift said movable switching means into contact with said fixed switching means and maintain said parts in this position but allowing said spring means to move the movable switching means automatically out of contact with the fixed switching means when the mine is not anchored.

3. A submarine mine comprising an electric firing circuit, contact devices which explode the mine automatically when struck by a moving body, a safety device controlled by the tension of the mooring cable which automatically makes or breaks the electric firing circuit, said safety device comprising a switch element located within the mine casing, a movable switch element also located within the mine casing, means which maintain said movable switch element out of contact with the fixed switch element when the mine is not anchored, a member con-

nected to said movable switch element which on the mine being anchored moves automatically relatively to the mine casing and closes the firing circuit of the mine, a pivoted lever, a connection from said pivoted lever to said mooring cable, and a delay action device which prevents the tension in the mooring cable from acting on said movable switch element until after a predetermined interval of time.

4. A submarine mine comprising an electric firing circuit, contact devices which explode the mine automatically when struck by a moving body, and a safety device, controlled by the tension of the mooring cable which automatically makes or breaks the electric firing circuit, said safety device comprising a switch element located within the mine casing, a movable switch element also located within the mine casing, means which maintain said movable switch element out of contact with the fixed switch element when the mine is not anchored, a slidable member which on the mine being anchored moves automatically upwards relatively to the mine casing and closes the firing circuit of the mine, a pivoted lever one end of which acts upon said member, and a connection from the other end of said pivoted lever to said mooring cable for controlling the automatic movement of said member, a flexible diaphragm surrounding said slid- able member which maintains the parts water-tight, a conical seating above said flexible diaphragm, said flexible diaphragm being adapted to be pushed upwards when the mine is anchored into contact with said conical seating for the purpose specified.

5. A submarine mine comprising an electric firing circuit, contact devices which explode the mine automatically when struck by a moving body, and a safety device controlled by the tension of the mooring cable which automatically makes or breaks the electric firing circuit, said safety device comprising a switch element located within the mine casing, a movable switch element also

cated within the mine casing, means which maintain said movable switch element out of contact with the fixed switch element 50 when the mine is not anchored, a member which on the mine being anchored moves automatically upwards relatively to the mine casing and closes the firing circuit of the mine, a pivoted lever one end of which 55 acts upon said member, a connection from the other end of said pivoted lever to said mooring cable, a flexible diaphragm surrounding said member which maintains the parts water-tight, a conical seating located above said flexible diaphragm, said flexible diaphragm being adapted to be pushed upwards against said conical seating both by the hydrostatic pressure and by the buoyancy pull on the mooring cable for the purpose specified.

6. A submarine mine of the kind comprising a flotation chamber, a sinker, a mooring rope connecting said flotation chamber and sinker, a detonator and primer, means for maintaining said detonator and primer out of the relative firing position until the mine has been launched and anchored to the sea bed, a sliding member, a pivoted lever connected to the mooring cable and acting on said sliding member, and means controlled by the upward movement of said sliding shaft due to pressure exerted by said pivoted lever for causing said detonator and primer to take up the relative 75 firing position.

7. A submarine mine comprising a casing attached to the lower part of the mine, a soluble plug located within said casing, said casing being provided with openings 85 through which water is allowed to enter and act on the soluble plug, a sliding member controlled by the tension on the mooring cable, and means controlled by the upward movement of said sliding member for bringing said plug opposite said openings so as to allow the sea water to act upon the same.

H. B. PRATT.
